APPARATUS FOR PERFORATING WELL CASINGS

Robert L. Klotz, Jr., Hazelton, Pa., assignor, by mesne assignments, to Borg-Warner Corporation, Chicago, Ill., a corporation of Illinois

Application February 19, 1947, Serial No. 729,655

8 Claims. (Cl. 102—20)

The present invention relates to apparatus for perforating well casings, particularly in connection with oil or gas wells. Specifically, the present invention relates to apparatus for more efficiently utilizing explosives in connection with perforating well casings.

There are several cases in the production of oil where well casing perforation is used. Thus, in the drilling of new wells, it is frequently desirable to case the bottom of a well, cement the cased well at the bottom to exclude water from the casing and then perforate the casing and cement to admit oil from the oil bearing formation into the casing. Again, it is frequently desirable to perforate a cased well at two or more points along the length of the borehole to permit oil to flow into the hole from two or more superimposed oil bearing formations.

Also, in the drilling for oil in the past, it was customary to drill through many deposits of oil which were not of the gusher variety so that when the well casings were sunk, such oil bearing deposits were rendered inaccessible so that the deeper lying more heavily yielding pockets of oil could be obtained. In recent years it has been found economically desirable and commercially feasible to obtain the oil contained in the oil deposits through which prior wells had been drilled. To eliminate the cost of drilling new holes for new wells, it would be desirable to utilize the existing wells and perforate the well casings at the level desired to afford access to the oil at the various levels through which the prior wells had been drilled and the casings sunk.

In connection with perforating oil well casings, it must be remembered that the casing must not be damaged. It must merely be provided with a plurality of perforations through which the oil contained in layers of the earth's surface through which the casing extends may enter the casing. Consequently, it is desirable to use explosive charges having a directionalized effect so as to produce a perforation rather than actual destruction of the casing wall. The well itself may be filled up with concrete or other suitable filling material to the desired level thereby closing the lower portion thereof whereby pumping of the oil obtained through these perforations may be more advantageously accomplished.

There has been developed a casing perforating gun which has had fairly widespread use. However, this casing perforating gun generally comprises special equipment not generally used by crews engaged in oil well and casing shooting. Furthermore, this perforating gun has been relatively expensive. It would be desirable to provide new and improved apparatus for casing perforations which employs the same type of equipment commonly employed by those engaged in oil well shooting and the like, while at the same time being much less complicated and expensive.

Accordingly, it is an object of the present invention to provide new and improved apparatus for perforating well casings.

It is another object of the present invention to pro-

2

vide apparatus for perforating well casings in which an explosive charge having laterally extending oppositely directed cavities therein for imparting opposed directionalization to the explosive energy developed upon detonation of the charge is employed.

It is another object of the present invention to provide apparatus for perforating well casings comprising a plurality of spaced charges arranged on a detonating element, each charge having oppositely directed cavities therein in order to provide a plurality of perforations at spaced points in the casing without damaging the casing.

Further objects and advantages of the present invention will become apparent as the following description proceeds and the features of novelty which characterize the invention will be pointed out with particularity in the claims annexed to and forming a part of this specification.

For a better understanding of the present invention reference may be had to the accompanying drawing in which Figure 1 is a sectional view somewhat schematic of the apparatus of the present invention disposed in a well for perforation of the same;

Figure 2 is an enlarged view of a small portion of Figure 1 showing a sectional view through one of the explosive units;

Figure 3 is a sectional view taken on line 3—3 of Figure 2 assuming that Figure 2 shows a complete device;

Figure 4 is a sectional view taken on line 4—4 of Figure 3;

Figure 5 is a view taken on line 5—5 of Figure 2 to show an end view of one explosive unit assuming that Figure 2 shows a complete device;

Figure 6 is a sectional view taken through an explosive unit illustrating a modification of the explosive unit shown in the prior figures of the drawings; and

Figure 7 is an enlarged sectional view of a portion of an explosive unit showing still another modification of the present invention.

Referring now to the drawing and more particularly to Figure 1 thereof, there is illustrated a cross-section taken through the earth's crust designated as 10. Extending down into the earth is a well 11 which is bounded by a tubular casing 12, generally in the form of a metal tube. It will be understood that the well 11 and the casing 12 extend down through the earth's crust and beyond the section of the earth designated as 10a, which has been found by suitable tests to contain oil deposits. It is desired to perforate the casing 12 where it passes through the oil bearing strata 10a without in any way damaging the casing, whereupon the lower section of the casing may be filled up with concrete or other suitable material and the oil in the oil bearing strata which enters the well 11 may be removed by suitable means well known to those skilled in the art.

Since such oil bearing strata are often of substantial thickness, it is desired to perforate the casing 12 over a substantial length thereof such as a length of from 5 to 10 feet or the like. In order that this casing 12 may be perforated throughout this length with the desired number of perforations without requiring a large number of successive perforating operations to be performed, there is provided in accordance with the present invention, a housing 13 which is in the form of a torpedo shell and which is of such a diameter as to be readily inserted in well casings such as 12. It has been found that for casings having an internal diameter of 6" or 8", that a torpedo shell or housing such as 13 having an external diameter of 4.8", is very satisfactory. According to Mechanical Engineers Handbook, Fourth Edition, the wall thicknesses for 6 inch casings varies from 0.280 inch to 0.69 inch and for 8 inch casings from 0.322 inch to 0.80

inch, depending upon whether the casing is made of steel or cast iron. It should be understood that the torpedo or housing 13 should be of such a construction as to either remain intact enough following detonation of the explosive to be described hereinafter so that it may be pulled out of the casing or else it should disintegrate sufficiently or be of such material that it is of no inconvenience in cleaning up the well following the casing perforation operation. If either one of these two conditions are not satisfied, it will be understood that the torpedo shell will remain as a serious obstruction within the well. The torpedo 13 could, for example, comprise a solid wooden member with the necessary bores to accommodate the explosive charges to be described herein-after. It might also comprise a plywood tube such as has been recently developed. As illustrated in the drawings, however, the torpedo shell or housing 13 comprises a metal casing having a configuration as is shown in Figure 1 in the drawing with the bottom closed as indicated at 13a and an open top designated as 13b.

In accordance with the present invention, there extends longitudinally of the shell or housing 13, an elongated detonating element 14 in the form of a cord capable of causing the substantially simultaneous detonation of a plurality of spaced charges connected at spaced points with said detonating element or cord 14. Such detonating elements are available on the market and one may be purchased under the trade name Primacord. As illustrated in Figure 1 of the drawings, a plurality of shaped explosive charge units generally designated as 15, are disposed along the detonating element 14, in equally spaced relationship. Each of the explosive units 15, as is best shown in Figure 2 of the drawings, comprises tubular containers 16 arranged with the axis thereof at substantially right angles to the detonating element 14. Each tubular container 16 contains an explosive charge, such, for example, as Seismogel A, manufactured by the E. I. du Pont de Nemours Company, to produce a directionalized explosive effect so as to perforate the casing 13 at each end of the tubular housing 16, as illustrated in Figures 1 to 3 of the drawings. Alternate units 15 disposed within the torpedo shell 13, are arranged with their axes at right angles as is clearly shown in Figure 1 of the drawings and as will be brought out in the description included hereinafter. If desired, alternate units 15 may be omitted and instead the remaining units may be of the form shown in Figure 6 designated at 15' and capable of producing four perforations instead of the two produced by the explosive units 15 to be described in greater detail hereinafter.

Before continuing the detailed description of the arrangement of the explosive units within the housing or torpedo shell 13, an understanding of the detailed construction of each explosive unit 15 is desirable and reference may now be had to Figures 2 through 5 of the drawings where such detailed construction is illustrated. Each tubular casing 16 is of such a length as to readily fit within the torpedo shell 13. The ends of the tubular members 16 are closed by end closure members 17 which include the upwardly and downwardly extending ears or flanges 17a. These ears 17a are in effect squaring flanges and serve to keep the explosive units 15 in an approximately horizontal plane when they are lowered into the shell 13 on the detonating cord or element 14.

It was discovered many years ago that a cavitated explosive charge causes the explosive force to be focussed along the axis of the cavitation in the charge. This directional effect or explosive phenomenon of cavitated charges has come to be known as the Munroe effect since it was discovered in 1888 by Charles G. Munroe. In accordance with the present invention, the Munroe effect is utilized by providing a cavity 18 in each end of the tubular member 16. For the purpose of controlling the size of the perforation the end of the cavity toward the detonating element 14 is closed by a cone shaped wall

19, preferably formed of metal or the like. The angle of the cone shaped member 19 may be varied in any desirable manner. For example, a 60 degree angle may be employed in which case a perforation of not more than about one-third the diameter of the explosive charge will be obtained. The size of the perforations can be controlled by changing the thickness of the cavity liner or the angle of the cone or by employing cone frustums or the like since the size of the perforations produced is determined by the shape of the hollow or cavity in the charge. Disposed between the two cone shaped walls 19 within the tubular member 16 is the explosive generally designated as 20 which may be inserted through a loading hole 21, formed at the upper center of the tubular member 16. The detonating element 14 extends through the loading hole or opening 21, and also through a smaller opening 22 at the lower part of the tubular member 16 of sufficient size to just accommodate the detonating element 14. With this arrangement any number of units 15 may be strung on the detonating element or fuse 14 at any reasonable intervals of space, and detonated substantially simultaneously.

In order to enhance the concentration and directionalization of the explosive energy developed by each charge upon detonation thereof, the cone-shaped walls of each cavity liner 19 are separated from the wall of the torpedo housing 13 by a predetermined stand-off distance. This is accomplished by extending the ends of the tubular member 16 beyond the mouths of the cavities defined by the liners 19 at each end of the explosive charges. If desired, the extended end portions of each tubular member 16 may be sealed off and evacuated to a low sub-atmospheric pressure in order further to enhance the degree of explosive energy concentration and directionalization.

For the purpose of supporting the explosive units 15 from the detonating element 14, any suitable fastening means may be employed. As illustrated in the drawing, the explosive units 15 are fastened to the detonating element 14 by means of friction tape, friction tape knots 23 and 24 being provided above and below respectively each explosive unit 15. If desired, a suitable closure may be provided for the loading hole 21, although the friction tape 23 at the upper end of the explosive unit 15 is generally satisfactory for both closing the loading hole 21 and for fastening the upper end of the tubular member 16 to the detonating element 14.

Although the friction tape knots designated at 23 and 24 associated with each explosive unit 15 will probably be entirely satisfactory to hold the explosive units 15 of Figure 1 in spaced relationship as shown, it may be desirable in some cases to provide wood beads disposed between the taped knots of the units along the detonating cord 14. When the plurality of units 15 have been mounted along the detonating element 14, as indicated in Figure 1 of the drawings, the string of units is lowered into the torpedo shell or housing 13. Preferably a fairly heavy weight 26 is fastened to the lower end of the detonating element 14 in order to maintain the detonating cord taut and insure that the explosive units 15 are held in proper spaced relationship. Preferably the space within the shell 13 between the spaced explosive units 15, is filled with a suitable pourable filling material comprising a plurality of discrete particles with interspersed air spaces such as sand designated at 27 in Figure 1 of the drawings. The housing may be taped or jarred to be sure that the sand is properly disposed. The sand filling is provided over the top of the uppermost explosive unit, as shown in Figure 1 of the drawings, and at that point an electric cap 28 is connected to the detonating element 14. This electric cap is preferably taped to the detonating element and wires leading to the cap 28 are fastened to a horizontal bar 29, extending across the upper open end of the shell or housing 13. Preferably this cross bar 29 is disposed a few inches from the top of the housing 13. Electrical connections are made from the cap 28 to the

shot cable 30 which may extend to any suitable detonating means such as 31 disposed above the surface at a safe distance from the well. The shell 13 is filled to the top with the filling material such as the sand 27. Under certain conditions it may be desirable to provide a lid or closure member for the top of the shell 13. For example, a tar seal formed of melted tar poured into the top of the shell 13a above the sand when cooled, provides a very desirable waterproof closure member. It is obviously necessary to keep the hot melted tar properly insulated and separate from the cap 28.

In addition to assisting in maintaining the explosive units in proper position in the housing, the filling material 27 performs several other important and desirable functions. First, it supports and reinforces the housing 13 against inward collapse under the external hydrostatic pressure of the fluid in the well, thus permitting the use of a housing of less wall thickness than could be used without filling material. It is obvious that a reduction in housing wall thickness reduces the amount of fragmentized material left in the well, and also reduces the amount of energy of the jet which is expended in perforating the housing. Secondly, the filling material serves to partially absorb and cushion the laterally directed shock waves developed by detonation of the explosive charges. This not only reduces the likelihood of damaging the well casing but also reduces the possibility that the shock wave from detonation of one charge may impinge on the next succeeding charge before the formation of its jet has been completed, with resultant deformation of the jet.

In order to insert the torpedo 13 into the well 11, suitable means not shown forming no part of the present invention may be employed. A lowering reel of some sort and a depth meter would be employed in the same manner as they are used in connection with equipment used heretofore.

Although the various parts of the apparatus for perforating well casings described above may have various shapes and sizes, it has been found for example that if a seven foot section of 6" casing is to be perforated with eight holes per vertical foot of length or in other words, a total of 56 holes, the torpedo housing 13 should be approximately eight feet in length and as mentioned above, about 4.8" in diameter. This shell could be loaded with double-ended explosive units such as 15 spaced every 3" or four-ended explosive units such as 15' to be described hereinafter spaced every 6". The detonating cord 14 would extend from 6" to 12" both above and below the topmost and bottommost explosive units 15. Preferably the tubular members 16 are in the neighborhood of 1" in diameter with a loading hole of about 1". As shown, each charge is approximately 3" in overall length and measures approximately 1 1/2" from the detonating cord 14 to each cavitated end of the charge. The opening 22 at the bottom of each tubular member 16 for the detonating element 14 should be approximately three tenths of an inch. The capacity for the explosive 20 in the tubular member 16 should be such as to take about .0865 lb., the maximum amount of explosive which will not damage the casing 12 being desirable. If the tubular member 16 had a diameter of eight tenths of an inch instead of an inch, the charge would have an explosive capacity of only about 64 percent of what it would have if the 1" tubular casing 16 were employed.

It will be understood that although the explosive units 15 described above are provided with two oppositely directed cavities 18, explosive units employing one cavity or more than one cavity may be employed. It is preferable to employ two or multiples of two cavities to provide opposed directionalization of the explosive energy upon detonation of the charge. Accordingly, in Figure 6 there is illustrated an explosive unit 15' having four cavities 34 and 35. The pair of cavities 34 are arranged in opposed relationship as are also the pair of cavities 35,

thereby providing laterally extending oppositely directed cavities for imparting opposed directionalization to the explosive energy developed upon detonation of the charge. The four-ended explosive units shown in Figure 6 of the drawings would require somewhat less explosive, due to the common mid-section, than two double-ended explosive units, and to this extent, would be preferred since the amount of explosive required is substantially reduced where a large number of units such as are shown in Figure 1 of the drawing are employed.

If difficulty is found in obtaining perforations of sufficient size and regularity, particularly if the amount of explosive must be reduced to prevent damage to the casing, then the arrangement shown in Figure 7 of the drawings may be employed. In this case a steel ball 36 of the desired size, preferably about one-half inch in diameter, is gummed as by means of gum 37 in the cone-shaped cavity 18, or if the four-ended explosive unit 15' of Figure 6 is employed, in the cavities 34 and 35. This steel ball 36 aids the portions of the cone such as the walls 19 thereof in producing the perforation in the well casing 12.

In view of the detailed description included above, the operation of the apparatus for perforating well casings described above, will be apparent and no further discussion is deemed necessary. With the present invention there is provided an arrangement for producing simultaneously a large number of perforations over a predetermined area of the well casing. Furthermore, this apparatus may be employed by any one having the experience and tools common to oil well shooting and casing shooting without recourse to special equipment, as has been the case heretofore. In addition, the arrangement described is considerably less expensive and produces results at least as satisfactory, if not more satisfactory than prior art arrangements.

While there have been disclosed particular embodiments of the present invention, it will be apparent that many changes and modifications thereof may be made. Accordingly, it is intended in the appended claims to cover all such changes and modifications as fall within the true spirit and scope of the present invention.

What is claimed as new and desired to be secured by Letters Patent of the United States is:

1. Well perforating apparatus comprising, in combination: an imperforate-walled housing adapted to be lowered into a well; a plurality of shaped explosive units, means mounting said units in said housing, each unit including an explosive charge having an outwardly facing cavity in at least one end thereof; means including detonating means interconnecting said units in assembled relation and positioning said units in positions spaced apart axially of said housing with their cavities facing the wall of said housing, said interconnecting and positioning means determining, independently of the said wall of said housing, the axial and angular spacing between adjacent units; said housing being of such material and wall thickness as to be perforated, upon detonation of said charges, without materially diminishing the well perforating effectiveness of said charges; and means for detonating said charges.

2. Apparatus as set forth in claim 1 wherein each explosive unit comprises a container and a charge of explosive therein having an outwardly facing cavity in at least one end thereof, said container having transversely aligned openings defining a transverse passage through the unit; and wherein said interconnecting and positioning means comprises an elongated element threaded through said transverse passages in each of said units in succession.

3. Apparatus as set forth in claim 1, wherein the unoccupied space within said housing is filled with a pourable filling material comprising discrete particles with interspersed air spaces cooperating with said interconnecting and positioning means to maintain the axial and angular spacing of said units.

4. Well perforating apparatus comprising, in combination: an imperforate-walled housing adapted to be lowered into a well; a plurality of shaped explosive units, means mounting said units in said housing, each unit including an explosive charge having an outwardly facing cavity in at least one end thereof and each having a transverse passage therethrough for reception of a detonating element; an elongated detonating element threaded through each of said passages in succession and positioning said units in assembled relation spaced apart axially of said housing with their cavities facing the wall of said housing, the axial and angular spacing between adjacent units being independent of the side wall of said housing, and said housing being of such material and wall thickness as to be perforated, upon detonation of said charges, without materially diminishing the well perforating effectiveness of said charges; and means including said detonating element for detonating said charges substantially simultaneously.

5. Well perforating apparatus comprising, in combination: an imperforate-walled housing adapted to be lowered into a well; a plurality of charge containers each of a length slightly less than the inner transverse dimension of said housing, means mounting said containers in said housing, each container having a transverse passage therethrough substantially in the median transverse plane thereof, said containers being positioned transversely in said housing with said passages in alignment substantially along the axis of said housing; an explosive charge in each container between its transverse passage and each end of the container, said charges having cavities therein facing each end of said containers; an elongated detonating element threaded through each of said passages; means coacting solely with said detonating element and said containers, and independently of said housing, for securing said containers in any desired spaced relation along said detonating element; and means including said detonating element for detonating said explosive charges substantially simultaneously.

6. Apparatus as set forth in claim 5, wherein each container is of generally cylindrical form and includes means at each end thereof cooperating with said housing to maintain the container with its axis substantially perpendicular to the axis of the housing.

7. Apparatus as set forth in claim 5, wherein the unoccupied space within said housing is filled with a pourable filling material comprising discrete particles with interespersed air spaces cooperating with said detonating element to maintain the axial and angular spacing of said units.

8. Apparatus as set forth in claim 4, including a pourable filling material filling the spaces between and around said units and cooperating with said detonating element to maintain the axial and angular spacing of the units.
